ATTORNEY.

UNITED STATES PATENT OFFICE.

CHRISTOPHER C. DONAHUE, OF BRIDGEPORT, CONNECTICUT.

HOSE-SUPPORTER.

1,378,663.

Specification of Letters Patent. Patented May 17, 1921.

Application filed December 2, 1920. Serial No. 427,727.

To all whom it may concern:

Be it known that I, CHRISTOPHER C. DONAHUE, a citizen of the United States, residing at the city of Bridgeport, in the county 5 of Fairfield and State of Connecticut, have invented certain new and useful Improvements in Hose-Supporters; and I do declare the following to be a full, clear, and exact description of the invention, such as 10 will enable others skilled in the art to which it appertains to make and use the same.

This invention relates to certain new and useful improvements in hose supporters and the primary object thereof is to provide 15 improved means for fastening the tape ends which dispenses with stitching or the clamping of same between metal parts.

A further object of the invention is to provide fastening means formed to receive 20 ornamental ribbons tied into knots or bows and to thus function in a dual manner.

Further and other objects will be later set forth and manifested in the course of the following description.

25. In the drawings:

Figure 1, is a front elevation of a hose supporter in accordance with the present invention;

Fig. 2 is a section in line 2—2 of Fig. 1, 30 and

Fig. 3, is a detail rear elevation of the structure at the top of Fig. 1.

In proceeding in accordance with the present invention, the tape 1 carries the 35 usual buckle 2, by looping the tape, the looped end being secured to the tape body by means of a pair of spaced double or twin eyelets. *i. e.*, each eyelet has two holes or eyes 3 which latter are spaced and are integrally 40 connected. As depicted in Fig. 3, the rear ends 4 of a two-piece ribbon are passed through the respective eyes of the eyelets on the front thereof and are then knotted or tied at the rear, whereupon the front ends 45 of the two ribbon pieces are tied together at the front to form a bow or knot 5. The rear ends of the ribbon pieces bridge the spaces between the eyes both at the front and rear of the eyes as Figs. 1 and 3 disclose.

50. In the instance of the clasp structure

which engages the hose, the tape 6 is looped about the bail 7 and secured by one of the twin eyelets as depicted in Fig. 2. In this instance, the ribbon is in one piece and has an intermediate part 8 bridging the space 55 between the rear of the eyes 3, 3 and the ribbon ends then passed forwardly through the eyelets and tied at 9 into a bow or knot which latter bridges the front space between the two eyes 3, 3.

In both forms of the invention, portions of the ribbons bridge the space between the front and the rear of each of the respective eyes of the twin eyelets. If desired a single ribbon can be used for the upper knot or 60 bow instead of the two pieces shown.

The eyelets thus perform a dual function, *i. e.*, they fasten the tape ends together, and they also provide supports for the ribbon bows or knots.

In addition, the provision of twin eyelets, provides a more effective securing of the tape ends, holding the ends against relative twisting, since as shown in Fig. 2, the eyelets grip the ends at spaced points.

The invention further eliminates the customary practice of forming holes or eyelets in the metal clasps themselves so as to receive the ribbon and at the same time affords a more positive securing means than the 80 usual stitching.

What is claimed is:

1. In a hose supporter, a tape having a looped end for supporting a metal part of the structure, an integral eyelet having 85 spaced eyes for securing the end of the loop to the tape body, and a ribbon threaded through each of the eyes and tied into a knot.

2. In a hose supporter, a tape having a looped end for supporting a metal part of the structure, and a pair of spaced eyelets for securing the end of the loop to the tape body, each eyelet being composed of a pair of spaced integral eyes, and a ribbon engaged through each of the eyes and tied into a bow.

In testimony whereof I affix my signature hereto.

CHRISTOPHER C. DONAHUE.
